US00D545912S

(12) United States Design Patent (10) Patent No.: US D545,912 S
(45) Date of Patent: * Jul. 3, 2007

(54) SIMULATED PILOTING GAME DEVICE

(75) Inventor: Hiroki Nunokawa, Tokyo (JP)

(73) Assignee: Sega Corporation, Tokyo (JP)

() Term: 14 Years

(21) Appl. No.: 29/261,397

(22) Filed: Jun. 14, 2006

(30) Foreign Application Priority Data

Dec. 14, 2005 (JP) 2005-036796

(51) LOC (8) Cl. 21-01

(52) U.S. Cl. D21/326

(57) CLAIM

The ornamental design for a simulated piloting game device, as shown and described.

DESCRIPTION

FIG. 1 is a front, top and right side perspective view of my new design for a simulated piloting game device;

FIG. 2 is a front elevational view of the simulated piloting game device of FIG. 1;

FIG. 3 is a rear elevational view of the simulated piloting game device of FIG. 1;

FIG. 4 is a right side elevational view of the simulated piloting game device of FIG. 1;

FIG. 5 is a left side elevational view of the simulated piloting game device of FIG. 1;

FIG. 6 is a top plan view of the simulated piloting game device of FIG. 1; and,

FIG. 7 is a bottom plan view of the simulated piloting game device of FIG. 1.
